(57) **CLAIM**

The ornamental design for a zipper pull, as shown and described.

DESCRIPTION

FIG. 1 provides a front view of the zipper pull, the back view being the same.

FIG. 2 provides a side view of the zipper pull, both sides being the same.

FIG. 3 provides a top view of the zipper pull; and, FIG. 4 illustrates a zipper pull in place on a piece of baggage. The broken line showing the piece of baggage and zipper sliders is for illustrative purposes only and forms no part of the claimed design.

1 Claim, 4 Drawing Sheets
